UNITED STATES PATENT OFFICE.

WILLIAM HENRY ROSE, OF BALTIMORE, MARYLAND.

COAT AND SIMILAR ARTICLE OF CLOTHING.

1,195,738.

Specification of Letters Patent. Patented Aug. 22, 1916.

Application filed May 7, 1915. Serial No. 26,468.

To all whom it may concern:

Be it known that I, WILLIAM HENRY ROSE, a citizen of the United States of America, and resident of Baltimore, Maryland, have 5 invented certain Improvements in Coats and Similar Articles of Clothing, of which the following is a specification.

This invention relates to the combination with a partly lined coat, or one having what 10 is termed a skeleton lining, an extension of the same which can be readily attached to, or removed from the said skeleton lining, thus altering the weight of the garment and adapting it for wear during different periods 15 of the year, or between seasons.

In the further description of the said invention which follows, reference is made to the accompanying drawing, forming a part hereof and in which:—

20 Figure 1 is an inside view of a coat provided with a detachable lining in accordance with the present invention, and Fig. 2 an inside view of the removable lining alone. Fig. 3 shows two views on an enlarged scale, 25 of a fastening device which is preferably used to connect the removable to the fixed or skeleton lining of the coat.

Referring now to the drawing, 1 is the coat proper, and 2 the skeleton lining which 30 is a fixture and found in all lined coats.

3 is a detachable extension of the skeleton lining, which at its upper edge is connected to the lining proper and at its sides and its lower edge to the hem *a* forming a part of the coat.

35

The fastening devices which are commonly in use, consist of the members *b* and *c* shown in Fig. 3 of the drawing, and they are so placed with respect to the skeleton lining, and its extension, and the coat, as 40 not to be visible.

I claim as my invention:—

• A coat provided with a permanent skeleton lining extending from the neck portion across the shoulders and to a point below 45 the arm openings, and free from the coat at its lower edge, in combination with a lining portion extending from the lower edge of the skeleton lining to the lower edge of the coat, said lining portion provided with 50 means at its upper lateral and bottom edges for detachably securing the same to the lower edge of the skeleton lining and the coat.

WILLIAM HENRY ROSE.
